CLAMP-AROUND VOLT-AMMETER

Harvey A. Schwartz, Merrick, and Franklin Jacoby, New York, N.Y., and Ernest Calafano, Maywood, N.J., assignors to Soss Manufacturing Company, Detroit, Mich., a corporation of Nevada

Filed Aug. 29, 1966, Ser. No. 3,620

Term of patent 14 years

(Cl. D26—1)

FIG. 1 is a front view of a clamp-around volt-ammeter showing our new design.

FIG. 2 is a rear view thereof.

FIG. 3 is a left side view of FIG. 1.

FIG. 4 is a right side view of FIG. 1.

FIG. 5 is a top view thereof.

FIG. 6 is a bottom view thereof.

We claim:

The ornamental design for a clamp-around volt-ammeter, as shown.
